UNITED STATES PATENT OFFICE

ROSSITER JOHNSON, OF NEW YORK, N. Y.

DESIGN FOR A PAPER WEIGHT

Application filed October 15, 1930. Serial No. 37,262. Term of patent 7 years.

To all whom it may concern:

Be it known that I, ROSSITER JOHNSON, a citizen of the United States, and a resident of New York city, borough of Manhattan, in the county of New York and State of New York, have invented the new, original, and ornamental Design for a Paper Weight, substantially as shown, of which the following is a specification.

Reference is had to the accompanying drawing, forming part thereof, wherein—

Figure 1 is a top plan view of a paper weight showing my new design;

Figure 2 is an edge view of the paper weight shown in Figure 1.

I claim—

The ornamental design for a paper weight

substantially as shown.

ROSSITER JOHNSON.
